CANE TYPE WEED KILLER OR SIMILAR ARTICLE

Paul A. Enblom, Eden Prairie, Minn., assignor to Judd Ringer Corporation, St. Louis Park, Minn., a corporation of Minnesota

Filed Oct. 6, 1965, Ser. No. 87,338

Term of patent 14 years

(Cl. D35—2)

FIGURE 1 is an isometric view of a cane type weed killer or similar article, showing my new design;

FIGURE 2 is an elevational view of the same with a portion broken away and on a somewhat larger scale than in FIGURE 1;

FIGURE 3 is a top plan view of the same; and

FIGURE 4 is a bottom plan view of the same.

The rear wall of the collar at the bottom of the body portion of the weed killer is substantially plain in appearance.

The dominant features of the design reside in the portions shown in full lines.

I claim:

The ornamental design for a cane type weed killer or similar article, as shown and described.
